(57) **CLAIM**

The ornamental design for a table, as shown and described.

DESCRIPTION

1.-4. Tables

1.1 is a perspective view of a first embodiment of a table in an erected position.

1.2 is a bottom perspective view of the table of 1.1 in the erected position.

1.3 is a front view of the table of 1.1 in the erected position.

1.4 is a bottom view of the table of 1.1 in the erected position.

1.5 is a right side view of the table of 1.1 in the erected position.

1.6 is a perspective view of the table of 1.1 in a collapsed position.

1.7 is a front view of the table of 1.1 in a collapsed position.

1.8 is a top view of the table of 1.1 in a collapsed position.

2.1 is a perspective view of a second embodiment of a table in an erected position.

2.2 is a bottom perspective view of the table of 2.1 in the erected position.

2.3 is a front view of the table of 2.1 in the erected position.

2.4 is a bottom view of the table of 2.1 in the erected position.

2.5 is a perspective view of the table of 2.1 in a collapsed position.

2.6 is a front view of the table of 2.1 in the collapsed position.

2.7 is a top view of the table of 2.1 in the collapsed position.

No protection is sought for the matter shown in dotted lines.

1 Claim, 11 Drawing Sheets
